CHURN SUPPORT

Forest L. Fulwider, Anamosa, Iowa

Application January 30, 1940, Serial No. 316,498

2 Claims. (Cl. 259—75)

This invention relates to churn supports and has for an object to provide a churn which may be mounted on the agitator of an oscillating type washing machine and in which butter is formed 5 in the cream container through the oscillation of the agitator.

A further object is to provide a device of this character which may be applied to various types of washing machines.

10 A further object is to provide a device of this character which will be formed of a few strong simple and durable parts, which will be inexpensive to manufacture, and which will not easily get out of order.

15 With the above and other objects in view the invention consists of certain novel details of construction and combinations of parts hereinafter fully described and claimed, it being understood that various modifications may be resorted to 20 within the scope of the appended claims without departing from the spirit or sacrificing any of the advantages of the invention.

In the accompanying drawing forming a part of this specification:

25 Figure 1 is a side elevation of a churn constructed in accordance with the invention and secured to an oscillating type agitator of a washing machine.

Figure 2 is a longitudinal sectional view taken 30 on the line 2—2 of Figure 3.

Figure 3 is a cross sectional view taken on the line 3—3 of Figure 2.

Figure 4 is a cross sectional view taken on the line 4—4 of Figure 3.

35 Referring now to the drawing in which like characters of reference designate similar parts in the various views, 10 designates a conventional agitator having a spindle 11, this agitator being illustrative of the conventional agitator of an 40 oscillating type of washing machine.

The churn forming the subject matter of this invention comprises a base 9 in the form of a metal disk which is equipped on the bottom with a soft rubber ring 12 corrugated as shown at 13 45 on its bottom face to prevent slipping on the agitator 11. A plurality of cross brace members 14 extend upwardly from the base 9 to a platform 15 formed of metal such as aluminum. The cor-

ners of the platform are formed with upstanding flanges 16 of right angular outline, as best shown in Figure 3.

The crossed brace members form a frame and within the frame are a plurality of spaced rubber rings 17 disposed co-axial with the frame. V-shaped strap brackets 18 are secured to respective crossed brace members by riveting or otherwise and are secured at the apex to a metal ring 20 which is of concave cross section 10 and which embraces the outer peripheral portion of a respective rubber ring 17.

5 The rubber rings 17 are adapted to receive the spindle 11 of the agitator and these rings may be of different sizes to receive spindles of 15 various diameters.

A cream container 21 is supported upon the platform, the container preferably being of rectangular cross section to be snugly confined on the platform between the flanges 16 and preferably being formed of glass.

During the operation of the washing machine to oscillate the agitator 10, the cream container 21 will be oscillated to form butter.

From the above description it is thought that 25 the construction and operation of the invention will be fully understood without further explanation.

What is claimed is:

1. A supporting frame comprising, a base, a soft rubber ring on the under side of the base, brace members extending upwardly from the base, a platform on the upper ends of the brace members, upstanding flanges on the platform, and a pair of superposed spaced rubber rings 35 disposed within the enclosure of the braces co-axial with the frame.

2. A supporting frame comprising, a metal plate forming a base, a soft rubber ring on the bottom of the base having a corrugated bottom 40 face, a plurality of crossed braces extending upwardly from the base, a platform on the upper ends of the braces, a pair of spaced rubber rings disposed co-axial with the frame, brackets extending from the braces, and concave rings carried by the brackets engaging the outer peripheral portions of the spaced rings.

FOREST L. FULWIDER.
